**METHOD OF PRODUCING GASOLINE HAVING
IMPROVED DISTRIBUTION OF ANTI-KNOCK
CAPABILITY**

CAPABILITY
Vernon O. Bowles, Katonah, N.Y., assignor to Socony
Mobil Oil Company, Inc., a corporation of New York
Filed Mar. 20, 1959, Ser. No. 800,715
4 Claims. (Cl. 208—93)

The present invention relates to the problem which arises when one or more cylinders of certain spark-ignited internal combustion engines knock although the octane rating of the gasoline supplied to the engine is high enough to provide knock-free operation.

In recent years it has been found that, although the octane rating of a gasoline is high enough to provide knock-free performance of certain spark-ignited, gasoline fueled, internal combustion engines, one or more of the cylinders thereof knock. This unexpected result is believed due to what is hereinafter designated "manifold distillation." 15 20

"Manifold distillation" as used herein designates that at least partial distillation of the gasoline in the engine manifold whereby a major portion of the lower boiling fraction of the gasoline goes to the cylinder or cylinders furthest from the gasoline inlet to the manifold and a major portion of the heaviest fraction of the gasoline goes to the cylinder or cylinders nearest the gasoline inlet to the manifold.

It is manifest that, as a result of "manifold distillation," when the octane ratings of the various fractions differ, those fractions the octane ratings of which are below that required for knock-free operation of the engine will cause those cylinders into which these fractions flow to knock. This is more readily recognized by reference to FIGURE 1.

Curve A of FIGURE 1 represents the relation of the octane rating of fractions of a gasoline having an octane rating of 90.8 (Research-1.9 cc. TEL/gal.) and the indicated mean average boiling point (M.A.B.P.). It will be seen, by reference to curve A, that those fractions of the 90.8 O.N. gasoline having a M.A.B.P. between about 150° F. and about 260° F. have octane rating of the order of 70.8 to 87.3 and represent about 52 percent of the gasoline (see FIGURE 2 and Table I). In the ensuing discussion this will be referred to as the "low octane valley," where the width of the valley is the percent by volume of the full boiling range gasoline in the valley and the depth of the valley is the weighted octane number of the total valley fraction. It is to be noted that there is one heavier, i.e., higher boiling, fraction the octane number of which is slightly under 90.8 but the octane number of this fraction is very near the octane number of the blend, and, not being in the valley, contributes little towards malperformance. This difficulty can partly be overcome by reforming the straight run gasoline to a higher octane level. Thus, for example, when the straight run gasoline is reformed to 96.2 octane number (Research-1.9 cc. TEL/gal.) only 42.5 percent of the gasoline has an octane rating below 90.8 (see FIGURE 3 and Table II). Furthermore, when straight run gasoline is reformed to 99.8 octane number (Research-1.9 cc. TEL/gal.), then only about 20 percent of the total gasoline has an octane rating below about 90.8 (see FIGURE 4 and Table III).

2

Table I

¹ Weighted octane number.

² It will be observed that this fraction, although having an octane rating less than 90.8, has been included with the fractions having octane ratings in excess of 90.8. This has been done because the fraction in question is a high boiling fraction and its effect will be compensated by the other high boiling fractions having an octane rating in excess of 90.8.

Table III

1 Wtd. O.N.—Weighted octane number

Table III

¹ Wtd. O.N.—Weighted octane number.

While reforming to a total octane number higher than the required octane number reduces the volume of the fraction of the total gasoline having an octane rating lower than the required octane rating, such a method for overcoming the problem of "manifold distillation" is costly and wasteful as will become evident from the following discussion.

One hundred barrels of gasoline having an octane rating of 90.8 (Research+1.9 cc. TEL/gal.) represents 9,080 octane barrels. When the straight run gasoline is reformed to 96.2 octane number (Research+1.9 cc. TEL/gal.) one hundred barrels represents 9,620 octane barrels. Similarly, when the straight run gasoline is reformed to 99.8 octane number (Research+1.9 cc. TEL/gal.) one hundred barrels represents 9,980 octane barrels. Thus, although the effect of "manifold distillation" tends to be overcome by reforming to an octane high enough to minimize the octane valley in the octane number vs. boiling point curve an appreciable number of octane barrels are given away. The width and depth of the low octane number valley as well as the number of octane barrels given away at various octane levels is manifest by inspection of Table IV. In passing it should be observed that the octane valley occurs in the lower boiling fraction of the blend and results in low "front end" octane number in spite of the high octane number of the lightest (C_5) fraction. It is also worthy of mention that TEL (tetraethyl lead) distillation tends to starve the front end fraction of TEL accentuating the octane rating deficiency of the front end and inefficiently provides an excessive amount of TEL to the "tail-end" fractions.

Table IV

[Required O.N. (Research+1.9 cc. TEL/gal.)—90.8]

Research +1.9 cc. TEL/gal.	Fraction of reformate, <90.8 O.N. (width)	Wtd. O.N. of fraction of reformate, <90.8 O.N. (depth)	Excess Octane, bbls./100 bbls. of reformate
90.8	.52	81.8	0
96.2	.425	82.1	540
99.8	.20	79.7	900

Thus, while "manifold distillation" can be overcome by reforming to a higher octane number it is inefficient because some of the cylinders are supplied with fuel the octane rating of which is in considerable excess of the octane rating which these cylinders can advantageously use and excess octane barrels essentially are given away. Thus, it is manifest that an efficient method of compensating or overcoming the effects of "manifold distillation" is necessary if valuable octane barrels are not to be given away.

One typical conventional method of processing involves the blending of normal C_4 hydrocarbons, light straight run gasoline, a reformate having an octane number (Research+1.9 cc. TEL/gal.) of 94.1, and a second reformate having an octane number (Research+1.9 cc. TEL/gal.) of 96.2 in the following proportions to provide a blend having an octane rating of 90.5 (Research+1.9 cc. TEL/gal.).

Percent

Normal C_4	4
Light straight run naphtha (78.7 O.N.)	30
94.1 O.N. reformate	40
96.2 O.N. reformate	26

However, as inspection of FIGURE 5 will make evident, the blend has an octane valley between 20.5 percent and 73.5 percent which will manifest itself in poor engine performance as the result of "manifold distillation." That is, the width of the octane valley is about 53 percent of the total gasoline blend.

It has been found that a simple, economical solution

to the problem of "manifold distillation" is provided by reforming a fraction of the whole straight run naphtha, preferably the fraction having an initial boiling point within the range of about 160° and about 220° F. and an end boiling point within the range of about 330° and about 420° F. under reforming conditions of severity such as to reduce the width of the "octane valley" to a practical minimum. In other words, the hereinbefore defined fraction of a straight run naphtha is reformed under reforming conditions to produce a reforate having an octane rating (Research+1.9 cc. TEL/gal.) greater than the required octane rating in which the width and depth of the "octane valley" are markedly reduced when compared to the octane valley in a reformate of required octane rating. The reforate having a markedly reduced or, when economically practical, no "octane valley" is then blended with an amount of unreformed heavy fraction of the straight run naphtha to produce a blend having the required octane rating. ("Heavy naphtha" is that fraction having an initial boiling point within the range of about 160° to about 325° F., preferably not below 225° F. and an end boiling point within the range of about 300° to about 425° F.) Preferably, the reforate is blended with a heavy naphtha fraction having a high initial boiling point, i.e., having an initial boiling point within the range of about 225° to about 275° F. or higher and an end boiling point within the range of about 330° to about 420° F. For example, to make gasoline having an octane rating of 90.2 (Research+1.9 cc. TEL/gal.) the reforate from a straight run naphtha from which a part of the heavy naphtha has been removed and having a boiling range of 100° to 380° F. is mixed with a separated fraction of straight run naphtha boiling in the range of 180° to 380° F., i.e., heavy naphtha, in the proportion set forth in Table V.

Table V

[Reformate from straight run naphtha BR 100°-380° F., O.N. (R+1.9 cc. TEL/gal.) 99.8 equals 80.3 percent. Heavy naphtha (from straight run), B.R. 180°-380° F. equals 19.7 percent]

Fraction No.	50% (vol.) lightest boiling fraction			50% (vol.) heaviest boiling fraction

9	.025	90.0	2.25	17	.055	36.8	
	.500		43.94		.500		45.77

55 NOTE.—Calculated octane of light 50% = 87.9. Calculated octane of heavy 50% = 91.5.

It will be observed that there are no excess octane barrels in the blend as prepared in the manner described. Consideration of the curve of FIGURE 5 will also make it evident that even when "manifold distillation" occurs there will be a more uniform distribution of the high, i.e., above 90.2, and the low, i.e., below 90.2, fractions of the blend to all of the cylinders of the engine. This is because the octane number of the lower boiling fifty percent of the blend is more nearly equal to the octane rating of the higher fifty percent fraction. It will be observed that the width of the octane valley has been reduced to about 25 volume percent of the blend composed, as shown in FIGURE 6, of the fractions having a M.A.B.P. (mean average boiling point) of about 130° to about 210° F. while a balancing fraction of about 10 volume percent having a M.A.B.P. of about 310° to about 350° F., and also having an octane number less than that of the blend (90.2) has resulted from introducing the unreformed heavy naphtha into the blend. Those skilled in the art

will also observe that the octane rating of the lighter fifty percent fraction of the blend is 87.9 which is only 3.6 octane numbers lower than the octane rating (91.5) of the heavier, fifty percent fraction of the blend. The difference between the actual octane number of the blend (90.2) and the calculated value (89.7) is the effect of blending appreciation in the light of present knowledge. This blending appreciation appears to apply equally to the light and to the heavy fifty percent fractions of the blend. Although all of the fuel passing through the engine manifold does not distill (a portion flows to the cylinders as a mist or fog) it is to be noted that any tetraethyl lead (which is relatively high boiling) in the blend will tend to remain with the higher boiling fifty percent fraction and appreciate the octane value of this fraction while concurrently depreciating the octane value of the lighter (manifold distilled) fifty percent fraction. The combination of tetraethyl lead distillation and fuel mist tends to be compensating. Thus, the comparison of the octane number of the lighter fifty percent fraction and the octane number of the heavier fifty percent fraction is a useful indication of the engine performance to be expected and achieved. Alternately, a satisfactory blend of characteristics similar to that of the aforescribed blend can be made by fractionating a straight run naphtha to obtain a C_5 -280° F. cut and a 280° to 380° F. fraction. All of the C_5 -280° F. cut and about 62.5 percent of the 280°-380° F. fraction is reformed to provide a reformate having an octane rating (Research+1.9 cc. TEL/gal.) of about 99.8. This reformate is then blended with the unreformed remainder of the 280°-380° F. fraction. Thus, for example, the straight run naphtha can be fractionated to give the following cuts in the ratio indicated.

Fraction	Percent volume	O.N. (R+1.9 cc.)
C_5 -280° F.	61.3	Immaterial
280°-380° F.	38.7	51

Since the octane rating of the straight run 280°-380° F. fraction is known and the octane rating of the reformate from the C_5 -280° F. and the reformed portion of the 280°-380° F. fraction has been agreed upon, the amount of unreformed 280°-380° F. fraction which can be blended is determined from the equation (assume octane rating (R+1.9 cc. TEL) of unreformed 280°-380° F. fraction is 51):

$$51X + 99.8(100-X) = 90.2 \times 100$$

$$-99.8X + 51X = 9020 - 9980$$

$$-48.8X = -960$$

$$X = 19.7$$

Since the yield when reforming the C_5 -380° F. fraction is known, it can readily be calculated how much of the 280°-380° F. fraction is to be reformed with the C_5 to 280° F. to 99.8 O.N. (R+1.9 cc.).

Reformate required @ 99.8 O.N. (R+1.9 cc.) to make 100 bbls. of 90.2 O.N. (R+1.9 cc.) when blended with 19.7 bbls. of 280°-380° F. fraction having O.N. (R+1.9 cc.) of 51—80.3 bbls.

Yield of 99.8 O.N. reformate from C_5 -280° F. enriched C_5 -380° F. straight run naphtha fraction—69.4% vol.

80.3
0.694 = 115.7 bbls. of C_5 -380° F./100 bbls. of 99.8 O.N. reformate

Bbls. of C_5 -280° F./100 bbls. C_5 -380° F. straight run naphtha = 61.3

Bbls. of C_5 -380° F./100 bbls. C_5 -380° F. straight run naphtha to be processed = 24.2

Accordingly, the present invention provides for reforming substantially all of the C_5 to 280° F. fraction of a straight run naphtha and a portion of the 280° to 380° F. frac-

tion of a straight run naphtha to the extinction or minimizing of the "octane" valley in the curve representing the relation between octane rating and mean average boiling point of various fractions of the reformed gasoline and blending with the reformate so obtained, the unreformed remainder of the 280° to 380° F. fraction of straight run naphtha to produce a blend having the required octane rating and an improved distribution of the octane rating over the distribution range of the blend.

- 10 Stated in another way the present invention provides for reforming substantially all of the C_5 to 280° F. fraction of a straight run naphtha and a portion of the 280° to 380° F. fraction of a straight run naphtha to an octane rating higher than the required octane rating of a gasoline to eliminate or minimize the portion of the C_5 to 280° F. having an octane rating substantially less, i.e., more than two octane units less, than the required octane rating of a gasoline and blending with the reformate so produced a portion of the 280° to 380° F. boiling range fraction of a straight run naphtha to produce a gasoline blend having the required octane rating, the aforesaid blend having not more than about 30 volume percent of the total blend boiling in the range C_5 to 280° F., having an octane rating substantially less than the required octane rating of the blend, the aforesaid blend having not more than about 20 percent of the total blend boiling in the range 280° F. to the end boiling point of the blend having an octane rating substantially less than the required octane rating of the blend. The amount of the 280°-380° F. fraction of the straight run naphtha which can be blended with the reformate from the reforming of the C_5 to 280° F. and a portion of the 280°-380° F. fraction of straight run naphtha is readily determined from the equation

$$NX + R(100-X) = 100K$$

$$-RX + NX = -100R + 100K$$

$$X = \frac{100(K-R)}{N-R}$$

where

40 N = octane rating of 280° to 380° F. fraction of straight run naphtha

R = octane rating of reformate from C_5 to 380° F. fraction of straight run naphtha

45 K = octane rating of blend

X = percent of 280° to 380° F. fraction in blend

100-X = percent of reformate from C_5 to 380° F. fraction

The C_5 -380° F. fraction to be reformed consists of all of the C_5 to 280° F. fraction and the balance of the 280° to 380° F. not used in the blend as unreformed, straight run naphtha.

50 In other words, the volume and the severity of reforming conditions is dependent upon the required octane rating of the blend and the octane rating of the 280° to 380° F. fraction of the unreformed, straight run naphtha.

55 A modification of the foregoing comprises fractionating the straight run naphtha into a C_5 to 160° F. fraction (A); a 160° to 320° F. fraction (B); and a 320-380° F. fraction (C).

60 All of the 160° to 320° F. fraction (B) plus a portion of the 320° to 380° F. fraction (C) is reformed to an octane rating greater than the required octane rating of the finished gasoline dependent upon the octane ratings of fractions A and C.

65 Accordingly, the present invention provides for (1) fractionating a straight run gasoline into at least two fractions the first fraction having an end boiling point of about 280° F. and the second fraction having an end boiling point of not more than about 380° F.; (2) reforming all of the said first fraction and a portion of the second fraction to obtain a reformate having an octane rating (Research+1.9 cc. TEL) higher than the required octane of the finished gasoline; (3) mixing said reformate and the balance of said second fraction to provide a blend having substantially the required octane rating, the bal-

ance of said second fraction to be admixed with the reformate being determined by the equation

$$X = \frac{100(R-K)}{N-R}$$

where,

N =octane rating of the 280° to 380° F. fraction of the straight run naphtha

R =octane rating of the reformate obtained from the first and a portion of the second fraction

K =the required octane rating of the blend, and

X =the percent of unreformed second fraction in the blend

Accordingly, the present invention provides a method for producing motor gasoline not more than about 30 percent of which has an octane rating more than 3 units below the octane rating of the whole gasoline which comprises fractionating a straight run gasoline into at least a light naphtha and a heavy naphtha having an initial boiling point in the range of the 160° to 325° F. and preferably not lower than 225° F., reforming at least a portion of the light naphtha together with a portion of the high boiling fraction top produce a reformate having an octane rating higher than the required octane rating ($R+1.9$ cc. TEL) of the blend and mixing the unreformed straight run gasoline with the aforesaid reformate to provide a blend having the required octane rating.

I claim:

1. A method of producing blended gasoline comprising catalytic reformate, straight run gasoline, and tetraethyl lead and having a required octane rating which comprises fractionating straight run naphtha to obtain fraction A comprising C_5 and heavier hydrocarbons having an end boiling point of about 160° F., fraction B comprising hydrocarbons boiling in the range of about 160° to about 320° F., and fraction C comprising hydrocarbons boiling in the range of about 320° to about 380° F., reforming all fraction B and a portion of fraction C, separating a reformate comprising C_5 and heavier hydrocarbons having an octane rating higher than said required octane rating of the aforesaid blended gasoline, mixing said reformate, fraction A, and the unreformed portion of fraction C, and obtaining blended gasoline having the aforesaid required octane rating of which blended gasoline not more than 30 percent by volume has an octane rating more than three octane rating units below the octane rating of the blended gasoline.

2. A method of producing blended gasoline comprising catalytic reformate and straight run gasoline and having a required octane rating which comprises fractionating a straight run gasoline to obtain a light fraction comprising C_5 and heavier hydrocarbons having an end boiling point of about 280° F., and a heavy fraction having a boiling range of about 280° to about 380° F., catalytically reforming substantially all of said light fraction and a minor portion of said heavy fraction to obtain C_5 to 280° F. reformate having a minimum portion thereof more than two octane units less than the required octane rating of a blend of C_5 and heavier reformate and the major portion of said heavy fraction, blending said reformate and the major portion of said heavy fraction, and obtaining a gasoline blend having the aforesaid required octane rating, having not more than 30 percent by vol-

ume boiling in the range C_5 to 280° F., and said not more than 30 percent having a rating more than three octane units below the required octane rating of said gasoline blend.

- 5 3. A method of producing blended gasoline comprising catalytic reformate and straight run gasoline and having a required octane rating which comprises fractionating straight run gasoline to obtain a heavy fraction having a boiling range of about 280° F. to about 380° F., and 10 a light fraction having an end boiling point of about 280° F., catalytically reforming substantially all of the hydrocarbons of said light fraction boiling in the range of C_5 to 280° F. and only a portion of the aforesaid heavy fraction under reforming conditions of temperature and 15 liquid hourly space velocity to minimize the "octane valley" in the curve representing the relation between octane rating and means average boiling point of the fractions of said reformed C_5 to 280° F. hydrocarbons to obtain a C_5+ reformate having a minimized "octane valley," blending said reformed hydrocarbons with the 20 balance of the unreformed heavy fraction of the aforesaid straight run gasoline and obtaining a gasoline blend of which gasoline blend not more than about thirty percent thereof boiling in the boiling range of the lightest 25 fifty percent has an octane rating 5 to 25 octane rating units below the aforesaid required octane rating.

4. A method of producing blended gasoline comprising catalytic reformate and straight run gasoline and having a required octane rating which comprises fractionating straight run gasoline to obtain a light fraction comprising C_5 and heavier hydrocarbons and having an end boiling point in the range of 225° to about 325° F. and a heavy fraction having an initial boiling point about the same as the end boiling point of the contemporaneously 30 fractionated light fraction and an end boiling point in the range of about 300° to about 420° F., catalytically reforming substantially all of said light fraction and a minor portion of said heavy fraction, obtaining a reformate comprising C_5 and heavier hydrocarbons having 35 a minor portion thereof more than two octane units less than the required octane rating of a blend of C_5 and heavier reformate and the major portion of said heavy fraction, mixing said reformate and the major portion of said heavy fraction, and obtaining a gasoline blend comprising C_5 and heavier hydrocarbons having not more than 40 30 percent by volume of the hydrocarbons boiling in the range of C_5 to 280° F. having an octane rating substantially less than the octane rating of said gasoline blend and having not more than about 20 percent by volume 45 of said gasoline blend boiling in the range 280° F. to the end boiling point of the blend having an octane rating substantially less than the required octane rating of the blend.
